UNITED STATES PATENT OFFICE.

ARTHUR TREVOR DAWSON AND GEORGE THOMAS BUCKHAM, OF WESTMINSTER, LONDON, ENGLAND, ASSIGNEES TO UNITED STATES ORDNANCE COMPANY, OF WASHINGTON, DISTRICT OF COLUMBIA, A CORPORATION OF VIRGINIA.

ORDNANCE BREECH MECHANISM.

1,326,580.

Specification of Letters Patent. Patented Dec. 30, 1919.

Application filed June 17, 1918. Serial No. 240,542.

To all whom it may concern:

Be it known that we, Sir ARTHUR TREVOR DAWSON, knight, and Sir GEORGE THOMAS BUCKHAM, knight, both subjects of the

5 King of Great Britain, residing at Vickers House, Broadway, Westminster, in the county of London, England, have invented certain new and useful Improvements in or Relating to Ordnance Breech Mechanism, 10 of which the following is a specification.

This invention relates to ordnance breech mechanism of the breech screw carrier type in which the carrier is provided with an actuating crank-shaft for unlocking the 15 breech screw; the invention is particularly applicable to breech mechanism of the kind forming the subject of the prior British Patent No. 6739 of 1912.

According to the invention we provide 20 means whereby the actuating crank-shaft can be removed from the carrier without necessitating the dismantling of any of the other parts of the breech mechanism. The said means may comprise a bearing (herein 25 termed the retaining bearing) between which and the actuating crank-shaft and in contact with both these parts a sleeve (herein termed the handlever sleeve) connected to the shaft is disposed; the said retaining 30 bearing is detachably held in position in a hole in the carrier which hole is of such size as to enable the crank of the actuating crank-shaft to pass through it. The retaining bearing and the handlever sleeve bear 35 at their inner ends against a collar or shoulder on the actuating crank-shaft and the retaining bearing bears at or near its outer end against a shoulder on the handlever sleeve, the said bearing and sleeve being 40 held in their assembled condition with respect to the crank shaft by suitable means which may comprise a nut on the crank shaft arranged in contact with the outer end of the sleeve.

45 In order that the said invention may be clearly understood and readily carried into effect we will describe the same more fully with reference to the accompanying drawings, in which:—

50 Figures 1 and 2 are respectively a rear and a side elevation showing the actuating crank-shaft and its associated parts in position in the carrier.

Fig. 3 is a section taken approximately on 55 the line 3—3 of Fig. 1.

Fig. 4 is a view similar to Fig. 3 but with the actuating crank-shaft, the retaining bearing, the hand lever and its sleeve, removed.

Fig. 5 is a horizontal longitudinal section 60 of the parts removed from Fig. 4.

Fig. 6 is a section taken approximately on the line 6—6 of Fig. 4, and

Fig. 7 is a rear elevation of the parts shown in Fig. 5. 65

A is the breech screw carrier, B is the actuating crank-shaft and B' is the actuating handlever. C is the aforesaid retaining bearing and D is the aforesaid handlever sleeve which is preferably made integral 70 with the actuating handlever and is connected by a feather and keyway to the crank-shaft B. b is the collar on the crank-shaft B against which collar the retaining bearing and the handlever sleeve bear at their 75 inner ends and d is the shoulder on the handlever sleeve against which the retaining bearing bears at or near its outer end. b' is the nut on the crank-shaft for holding the retaining bearing and the handlever 80 sleeve in the assembled condition with respect to the crank-shaft.

The carrier A is formed with the hole A' which as aforesaid is of such shape and size as to permit the crank of the crankshaft B 85 to pass readily through it. This hole receives the retaining bearing C which has at its inner part a projection C' adapted to rest on a flat portion a' of the lower wall of the hole A'. The said retaining bearing 90 has at its outer part a tail-piece C² which fits within a correspondingly shaped recess A² in the lower wall of the hole A'. The tail piece serves to receive a securing pin c which passes through the contiguous part of 95 the carrier to lock the retaining bearing C in position.

The aforesaid nut b' that is screwed on the outer end of the crank shaft B, is disposed within a cavity in the outer end of the handlever sleeve D and by bearing against the inner wall of this cavity, serves to hold the said sleeve in position between the nut and the collar b on the inner end of the crank shaft and also to hold the retaining bearing C in position between the sleeve D and the said collar. 100

To remove the actuating crank-shaft B from the carrier it is merely necessary to detach the securing pin c, whereupon the said 110

shaft, the retaining bearing C, the handlever sleeve D and the handlever B' can be displaced outwardly and withdrawn as a single unit (see Figs. 5 and 7). These parts 5 can then be readily dismantled by removing the nut b'.

What we claim and desire to secure by Letters Patent of the United States is:—

1. In ordnance breech mechanism of the 10 breech screw carrier type, the combination of a carrier having a passage therein, and a breech screw actuating crank shaft detachably secured in the passage, said passage being of sufficient size to enable the 15 crank of the actuating crank shaft to pass through it.

2. In ordnance breech mechanism of the breech screw carrier type, the combination 20 of a breech screw actuating crank shaft, a carrier having a passage therein of sufficient size to enable the crank of the actuating crank shaft to pass through it, and a bearing detachably secured in said passage and in which the crank shaft rotates.

3. In ordnance breech mechanism of the 25 breech screw carrier type, the combination of a breech screw actuating crank shaft, a carrier having a passage therein of sufficient size to enable the crank of the actuating 30 crank shaft to pass through it, a bearing detachably secured in said passage and in which the crank shaft rotates, a sleeve be-

tween the bearing and crank shaft connected to the latter, and an actuating hand lever fixed to the sleeve.

4. In ordnance breech mechanism of the breech screw carrier type, the combination 40 of a breech screw actuating crank shaft, a carrier having a passage therein of sufficient size to enable the crank of the actuating crank shaft to pass through it, a bearing detachably secured in said passage and in which the crank shaft rotates, a sleeve between the bearing and crank shaft connected to the latter, and an actuating hand lever 45 integral with the sleeve.

5. In ordnance breech mechanism of the breech screw carrier type, the combination 50 of a breech screw actuating crank shaft provided with a collar, a carrier having a passage therein of sufficient size to enable the crank of the actuating crank shaft to pass through it, a bearing provided with an interior shoulder detachably secured in said passage with its inner end in engagement 55 with the collar and in which said shaft rotates, a sleeve between the bearing and crank shaft connected to the latter and having its inner end in engagement with the collar, an exterior shoulder on the sleeve abutting 60 the shoulder of the bearing, and an actuating hand lever fixed to the sleeve.

ARTHUR TREVOR DAWSON.
GEORGE THOMAS BUCKHAM.
